UNITED STATES PATENT OFFICE.

WILLIAM E. HERON, OF GREAT FALLS, MONTANA.

DESIGN FOR AN ORNAMENTAL CARD.

SPECIFICATION forming part of Design No. 26,538, dated January 19, 1897.

Application filed December 5, 1896. Serial No. 614,658. Term of patent 7 years.

To all whom it may concern:

Be it known that I, WILLIAM E. HERON, a citizen of the United States, residing at Great Falls, in the county of Cascade and State of Montana, have invented and produced a certain new and original Design for Ornamental Cards; and I do declare the following to be a full, clear, and exact description of the invention, such as will enable others skilled in the art to which it appertains to make and use the same.

My invention relates to a new and original design for an ornamental card, such as is used for visiting, Christmas, New Year, birthday, or memento cards. It relates to the entire configuration of the card.

My design relates to a card, as illustrated in the accompanying drawing, in which the figure is a perspective representation of a card embodying my design.

The leading features of my design appear in the following description.

1 I represents the approximately rectangular base, having one corner turned upward and over to form a scroll 2, while from the opposite diagonal corners 3 4 is a semicircular bow 5, formed of a single spiral.

6 is a representation of a fungus growth springing out of the base and joining with the bow 5.

Having thus fully described my invention, what I claim as new and original, and desire to secure by Letters Patent of the United States, is--

The design for a card, substantially as shown and described.

In testimony whereof I hereunto affix my signature in presence of two witnesses.

WILLIAM E. HERON.
